UNITED STATES PATENT OFFICE.

HERMAN THINGGAARD, OF CHICAGO, ILLINOIS.

CLASP.

1,281,880.

Specification of Letters Patent. Patented Oct. 15, 1918.

Application filed May 13, 1918. Serial No. 234,275.

To all whom it may concern:

Be it known that I, HERMAN THINGGAARD, a citizen of the United States, residing at Chicago, county of Cook, and State 5 of Illinois, have invented certain new and useful Improvements in Clasps, of which the following is a specification.

This invention relates to improvements in clasps, and particularly to improvements 10 in clasps which are ordinarily applied to garments.

An object of the invention is to provide clasps elements with integral portions permitting permanent attachment of the elements 15 to the fabric of the garment.

Another object of the invention is to provide the elements of the clasp with studs which may be inserted in suitable openings made for this purpose in the garment from 20 one side, and which may be flared after insertion so as to prevent withdrawal of the clasp element after insertion.

Another object of the invention is to provide clasp elements with portions which 25 will facilitate the location of said elements with respect to certain parts of the garment and which thereby facilitate proper registration of the elements when it is desired to bring the same into closing position.

With these and other objects in view an 30 embodiment of the invention has been described in the following specification and illustrated in the accompanying drawing, wherein—

Figure 1 shows a portion of a garment with the clasp attached thereto;

Fig. 2 shows on a larger scale the fastening portion of a garment clasp element;

Fig. 3 is a front view of one of the clasp 40 elements;

Fig. 4 is a longitudinal central section through the same detached;

Fig. 5 is a longitudinal section through the same clasp element combined with the 45 fabric portion to which said element has been permanently secured;

Fig. 6 is a front view of the companion clasp element;

Fig. 7 is a longitudinal section through the same clasp element detached, and 50

Fig. 8 shows the end section of this clasp attached to a portion of a garment.

The clasp, including a catch 1 and a hook 2, preferably is made of sheet metal, each of these elements being provided with lugs 55 3 from which hollow studs or rivet stems 4 project, preferably in a direction away from the main portion of the clasp element.

These hollow stems or studs 4 may be inserted into the body of the fabric after 60 the same has been provided with suitable holes, and the portion of the stem projecting from the opposite surface of the garment may then be bent over outwardly as shown at 5 so as to split the projecting 65 flange in a number of places and forming a head, which will prevent the withdrawal of the clasp element from the garment into which it has been inserted. The formation of these flared flange portions or the head 70 5 on the opposite side of the garment may be attained by suitable punches or other pressing tools of known or approved construction, not shown.

For the purpose of facilitating the location of these clasp elements, each of the elements is provided with a marking portion deviating in its shape slightly from the adjacent portion of the clasp. From Figs. 1, 2, 3, and 6, for instance, it will be seen 80 that one of the edges of the clasp 1 has a notch 9, and in securing this clasp element to the garment the notch 9 may be brought into a position in which it overlies a well defined portion of the garment, as, for instance, the seam 10, near the upper edge of the trousers to which this clasp is shown applied in the present instance.

A similar marking portion or notch 11 is provided on the companion clasp element 2, 90 and if this portion is also brought into a position in which it overlies a part of the seam 10 it is obvious that the two clasp elements 1 and 2 can be brought to closing position without disturbing the fit of the 95 garment.

I claim:

A garment clasp consisting of catch and hook elements, lugs formed on the opposite ends of said elements and having integral rivets in connection therewith, adapted to be enlarged at the opposite surface of the garment, said catch and hook elements being formed with centrally disposed marking portions adapted for registration to de-

fine the proper location of one element with the other and with respect to a predetermined portion of the garment.

In testimony whereof I affix my signature in the presence of two witnesses.

HERMAN THINGGAARD.

Witnesses:

DANIEL A. BRENNAN,
ESTER SYNWOLT.
